UNITED STATES PATENT OFFICE

ROBERT J. PARDEE, OF CLEVELAND HEIGHTS, OHIO, ASSIGNOR TO THE CLEVELAND PUNCH & SHEAR WORKS COMPANY, OF CLEVELAND, OHIO, A CORPORATION OF OHIO

DRAW PRESS

Application filed April 9, 1932. Serial No. 604,239.

This invention relates generally to draw presses and more particularly to a draw press in which the blank holder and the drawing or forming die are operated from the slide and the blank holder is yieldably connected with the slide so as to yield when the pressure on the blank holder exceeds a predetermined amount.

In draw presses heretofore generally known it has been customary to drive the forming die and blank holder from the main shaft of the press. It also has been customary to provide a system of links and levers to cause the blank holder to dwell for a definite period in holding contact with the work during the drawing or punching operations. These links and levers have usually been complicated in construction and design and expensive to manufacture. In order to simplify the construction and operation and to reduce the cost of manufacture, I have provided a draw press in which the blank holder and forming die are both driven from the same connecting rod and in which the blank holder is yieldably or slidably mounted within the slide so that the pressure of the blank holder against the work is constant but may be varied, if desired.

One of the main objects of the invention therefore is to simplify the construction and design of a draw press and to provide a draw press in which the number of parts are reduced to a minimum and the cost of production is likewise reduced.

Another object of the invention is to provide a draw press in which the forming die and blank holder are both operated from the slide and in which a hydraulic yieldable connection is provided between the blank holder and the slide whereby the blank holder may yield when the pressure thereon exceeds a predetermined amount.

Another object of the invention is to provide a draw press of the character described in which the blank holder is slidably and yieldably mounted in the slide and connected with the accumulator by means of a rigid connection which extends into the slide and permits movement of the slide with respect thereto.

Further and more limited objects of the invention will appear as the description proceeds and by reference to the accompanying drawings in which Fig. 1 is a view in front elevation of my improved draw press; Fig. 2 is a vertical sectional view; Fig. 3 is a view similar to Fig. 2 with the parts in different position; and Fig. 4 is a view showing the accumulator and the connections between the accumulator and the slide.

Referring now to the drawings, the draw press consists essentially of a base member 1 on which is mounted a die block 2 which supports a die 3. Journaled in the upper portion of the draw press is a shaft 4 having a crank portion 5 to which is connected a connecting rod 6. The press is adapted to be operated by means of a motor 7 which drives a gear 8 mounted on a shaft 9 which in turn drives the drive shaft 4 through suitable mechanism including the large gear 10. Slidably mounted on the draw press is a cross head or slide 11 which is disposed between guide blocks 12 and 13. The cross head or slide 11 is operatively connected with the crank portion 5 of the shaft 4 by means of a connecting rod 6 and pin 6^a. The slide is provided with a cylindrical opening 14 in which is mounted a piston 15 having a central bore therein through which extends a plunger or forming die 16 the lower end 17 of which is somewhat larger than the portion 16. Carried by the plunger or piston 15 is a blank holder 18 which is secured thereto by means of tie rods 19 and 20 and nuts 19^a and 20^a. The slide 11 is provided at one side thereof with a chamber 21 which is connected with the cylindrical opening 14 by means of a bore or passageway 22.

Disposed at the top of the draw press and extending transversely thereof is a supporting bar or member 23 having an opening therein through which extends a rigid tubular connection 24 having an opening 25 therein. The tubular member 24 extends through a bore or opening provided in the slide 11 and the opening 25 is disposed in constant open communication with the chamber 21. The tubular member 24 is secured in place by means of a nut 26 and the axis of the tubular

member is disposed parallel to the direction of movement of the slide. Suitable packing glands 27 and 28 are provided about the tubular member to prevent leakage thereabout.

5. Connected with the upper end of the tubular member 24 is a rigid connection 29 which is secured to the tubular member 26 by means of a union 30. The connection 29 leads to an accumulator the purpose of which will be 70 hereinafter described.

The slide or cross head 11 is reciprocated by the shaft 4 and crank 5 and has a working fit with the tubular member 24 which extends therethrough. The blank holder 18 is oper- 75

15. atively connected with the piston 15 and is adapted to engage the work and hold it in position on the die 3. The slide 11 has a fixed stroke determined by the length of the crank 5.

20. The work is positioned on the die 3 and as the slide moves downwardly, the blank holder 18 engages the work while the forming die 17 continues its downward movement and produces the drawing operation.

25. The rigid connection 29 connects with an accumulator 31 from which leads a connection 32 which connects with a pressure tank 33. The connection 29 is provided with a pressure indicator 34 and a manually oper- 80

30. able valve 35. Leading downwardly from the accumulator 31 is a tubular connection 36 to which the lower end of the connection 29 is secured. From the construction and connections just described, it will be seen that the 85 opening 14 into which the piston 15 is slidably secured is in constant open communication with the accumulator 31.

35. Due to the high pressure frequently obtained in the accumulator and in the connections between the accumulator and the space 90 in front of the piston 15, it becomes necessary to provide the rigid connections just described.

40. In the ordinary operation of the draw press a predetermined pressure is supplied 95 to the air pressure chamber 33 which in turn exercises a predetermined pressure upon the accumulator 31 which preferably contains a liquid. This pressure is also exerted upon the piston 15 when the valve 35 in the connection 29 is open.

45. It will therefore be seen that the pressure on the blank holder is constant and the same as the pressure within the accumulator. This pressure of course can be 100 varied by varying the pressure within the accumulator and when the pressure on the blank holder exceeds a predetermined amount, the blank holder may yield or move with respect to the slide. Upon the upward

50. movement of the slide, the enlarged portion 105 of the forming die engages the piston 15 and moves with the slide from the position shown in Fig. 3 to the position shown in Fig. 2.

55. It will now be seen that I have provided a

draw press which will accomplish the objects of the invention as hereinbefore stated, which will be simple in construction, safe and dependable in operation and which at the same time will provide for the dwell of the blank holder and also permit the pressure on the blank holder to be varied as desired. 70

Various changes may be made in the details of construction and arrangement of parts without departing from the spirit of my invention and the embodiment of the invention herein disclosed is merely illustrative and not to be considered in a limiting sense as the invention is limited only in accordance with the scope of the appended claims. 75 80

Having thus described my invention, what I claim is:

1. In a draw press, the combination of a shaft, a slide operatively connected with said shaft so as to be reciprocated thereby and having a forming die rigidly connected therewith, a blank holder slidably mounted in said slide, an accumulator, a connection between said accumulator and said blank holder so as to permit a movement of the blank holder with respect to said slide, said connection including a conduit extending through said slide and disposed in open communication with the space in front of said blank holder. 90 95

2. In a draw press, the combination of a shaft, a slide operatively connected with said shaft and slidably supported on the frame of the press, an accumulator, a connection leading from said accumulator and extending through said slide, a forming die rigidly connected with said slide, said slide having an opening therein, a piston yieldably mounted in said opening, a blank holder operatively connected with said piston, means connecting said connection with the opening in said slide in front of said piston whereby said piston may move with respect to said slide when the pressure exceeds a predetermined amount. 100 105

3. In a draw press, the combination of a shaft, a slide operatively connected with said shaft so as to have a fixed stroke and having a forming die connected therewith, said slide having an opening therein, a blank holder slidably mounted in said opening and adapted for movement with respect to said slide, an accumulator, and means providing a constant open communication between said accumulator and the space in front of said blank holder, said means including a rigid conduit extending into said slide. 110 115 120

4. In a draw press, the combination of a shaft, a slide operatively connected with said shaft so as to have a fixed stroke and having a forming die connected therewith, said slide having an opening therein, a blank holder slidably mounted in said opening and adapted for movement with respect to said slide, an accumulator, and means providing a constant 125 130

open communication between said accumulator and the space in front of said blank holder and including a rigid conduit extending through said slide and connected with
5 said opening.

In testimony whereof, I hereunto affix my
signature.

ROBERT J. PARDEE.
